UNITED STATES PATENT OFFICE

ERNEST H. SCHMIDT, OF CLEVELAND, OHIO, ASSIGNEE TO THE NATIONAL MALLEABLE
CASTINGS COMPANY, OF CLEVELAND, OHIO, A CORPORATION OF OHIO.

DRAFT-RIGGING.

1,104,554.

Specification of Letters Patent. Patented July 21, 1914.

Application filed November 29, 1910. Serial No. 594,690.

To all whom it may concern:

Be it known that I, ERNEST H. SCHMIDT, a citizen of the United States, and a resident of Cleveland, in the county of Cuyahoga and 5 State of Ohio, have invented a new and useful Improvement in Draft-Riggings, of which the following is a full, clear, and exact description, reference being had to the accompanying drawings, forming part of 10 this specification, in which—

Figure 1 is a plan view of my improved rigging, associated with my preferred form of coupler; Fig. 2 is a sectional plan view of the same; Fig. 3 is a longitudinal vertical section of the draft rigging; and Figs. 4, 5, 6 and 7 are cross sections on the lines IV—IV, V—V, VI—VI and VII—VII, respectively, of Fig. 3.

My invention relates to draft riggings to 20 sustain buffing and pulling stresses in coupler mechanisms for railway cars and is designed to provide a simple and effective device of this character.

One object of the invention is to provide a 25 tandem gear in which the combined capacity of the springs is utilized for both buffing and draft.

In the drawings, 2 represents a draft member in the form of a case which extends 30 rearwardly from the coupler shank and may be either integral therewith or attached thereto. This case is provided with lateral slots 3, through which extend keys 4, 5 and 6, having sliding engagement with the walls 35 of the slots. These keys may be secured in position by cotter pins 7. Extending longitudinally within this case is a plunger 8, of cruciform shape, shown as having an integral rear boss portion 9, with a vertically extending pivot hole 10, by which the device 40 may be pivoted to a portion of the car frame, so as to swing horizontally and radially. The plunger member 8 is also provided with horizontal slots through which the keys 4, 45 5 and 6 pass, the forward slot 11 being elongated rearwardly, while the rear slot 12 is elongated forwardly, the middle slot fitting lightly upon its key, as shown in Figs. 2 and 3.

50 Springs 13 and 14 surround the plunger member within the casing and between the keys, these being adapted to be operated both in buffing and in draft. The forward spring 13 engages at its front end with two pins 15, which are insertible at the sides and

held by suitable cotters. These pins form an abutment rigid with the draft member against forward movement of the spring 13. The rear end of this forward spring 13 bears against a follower 16, whose cross sectional shape is shown in Fig. 5, having upper and lower wing portions 17 and 18, which project upwardly and downwardly through top and bottom slots in the casing. The follower 19 at the front end of the rear 65 spring 14 is of the same shape as the follower 16, and these followers are inserted by pushing them through the open end of the draft member and then rotating them and tipping them into proper position to 70 enter the top and bottom slots of the draft member. When in proper position, the top and bottom wings of these followers abut against the top and bottom wall portions 20 of the casing and against the opposite sides 75 of the key 5. The follower 16 can, therefore, move forwardly but not rearwardly, while the reverse is true of the rear follower 19. The rear spring bears at its rear end against a shoulder 21 on the plunger 80 member 8.

The operation in buffing is as follows: When the coupler is driven rearwardly in buffing, the plunger being rigidly fixed to the car and the key 5 being rigidly attached 85 thereto, the forward spring will be compressed against the follower 16 and the key 5 by the rearward movement of the key 4, which is carried rearwardly by the movement of the draft casing. At the same time, 90 the rear spring 14 will be compressed by the rearward movement of the follower 19, being moved by the wall portions 20 of the case, while the rear end of the spring is prevented from movement by the abutment of 95 the plunger 8, against which the key 6 has a bearing. The action is much the same in pulling. In this case, the key 4 is prevented from forward movement and the spring 13 is compressed by forward movement of the 100 front follower 16, which now moves away from the immovable key 5. The spring 14 is compressed against the follower 19, which is held immovable by the key 5, by the forward movement of the key 6, which is carried by the draft member 2.

The advantages of my invention will be obvious to those skilled in the art, since a simple and effective draft gear is provided which utilizes the capacity of the tandem 110

springs both in pulling and in draft. The parts are simple and not liable to get out of order and the device may be cheaply made and assembled.

5 Various changes may be made in the details of construction and arrangement of the parts without departing from the spirit and scope of my invention as defined in the appended claims.

10 I claim:

1. In a draft rigging, a plunger member adapted to be connected to a car frame, a draft member having coupling means at its forward end and provided with a casing portion at its rear end portion which telescopes over the plunger member, a plurality of keys connecting said members, the members being slotted to permit endwise movement of the draft member, and a plurality of 15 springs arranged in tandem and within said casing portion and provided with bearings whereby they sustain both buffing and pulling stresses, one bearing of each spring being carried by the plunger and the other bearing of each spring being carried by the draft member substantially as described.

2. In a draft rigging, a plunger member adapted to be pivotally connected to a car frame, a draft member having a casing portion telescoping over the plunger member and arranged to swing therewith, three keys extending through the casing portion of the draft member and the plunger member, the casing portion and plunger member having 20 elongated slots to receive the front and rear keys, and the casing portion only having an elongated slot to receive the intermediate key, two springs seated within the casing portion between the keys, the forward spring 25

having a rigid bearing on the plunger member at its forward end and the rear spring having a rigid bearing on the plunger member at its rear end, and bearings for the inner ends of the springs seated against the intermediate key, substantially as described. 40

3. In a draft rigging, a plunger member adapted to be connected to a car frame, a draft member provided with coupling means and having a casing portion fitting telescopic over the plunger member, a forward key extending through the draft and plunger members and normally fixed against forward movement, but capable of rearward movement, a rear key also extending through the draft and plunger members and normally held against rearward movement but capable of forward movement, an intermediate key member connecting the plunger and draft members and held against both forward and rearward movement, springs 50 arranged in tandem within the casing portion of the draft member, the rear spring having at all times a bearing against the rear key at its rear end and the forward spring having at all times a bearing upon 55 the forward key at its forward end, and followers forming abutments for the adjacent ends of said springs, said followers seating against the intermediate key and having a movable engagement with the draft member, substantially as described. 60

In testimony whereof, I have hereunto set my hand.

ERNEST H. SCHMIDT.
